DESIGN FOR AN OVEN FRONT

Irwin Elliott, Harmon, N. Y., assignor to Universal Oven Company, Incorporated, New York, N. Y., a corporation of New York

Application January 18, 1936, Serial No. 60,648

Term of patent 14 years

To all whom it may concern:

Be it known that I, Irwin Elliott, a citizen of the United States, residing at Harmon, in the county of Westchester and State of New York, have invented a new, original, and ornamental Design for an Oven Front, of which the following is a specification, reference being had to the accompanying drawing, forming a part thereof and in which:

Fig. 1 is a perspective view of an oven front showing my new design;

Fig. 2 is a face view thereof.

In the accompanying drawing, I have shown the novel design of oven front, the doors A of the front closing the oven.

I claim:

The ornamental design for an oven front, substantially as illustrated and described.

IRWIN ELLIOTT.
